HYDRAULIC JACK

Watt B. Bair, 4425 Ventura Canyon Ave.,
Sherman Oaks, Calif.

Filed May 3, 1965, Ser. No. 85,086

Term of patent 14 years

(Cl. D41—1)

FIG. 1 is a perspective view of a hydraulic jack in operative position;

FIG. 2 is a side elevational view thereof in operative position;

FIG. 3 is a top plan view thereof; and

FIG. 4 is a side view showing the hydraulic jack in inoperative position.

The dominant features of the design reside in the solid line portion, the broken line showing of a channel member being for illustrative purposes only.

I claim:

The ornamental design for a hydraulic jack, as shown and described.
